UNITED STATES PATENT OFFICE.

HENRY VAN HOEVENBERGH, OF ELIZABETH, NEW JERSEY.

PRINTING-TELEGRAPH.

SPECIFICATION forming part of Letters Patent No. 241,094, dated May 3, 1881.

Application filed October 25, 1880. (No model.)

To all whom it may concern:

Be it known that I, HENRY VAN HOEVENBERGH, a citizen of the United States, residing at Elizabeth, in the county of Union and State of New Jersey, have invented certain new and useful Improvements in Printing-Telegraphs; and I do hereby declare the following to be a full, clear, and exact description thereof, reference being had to the accompanying drawings.

10 My invention relates especially to that class of printing-telegraphs which are designed to be operated automatically by means of electric pulsations proceeding from a suitable transmitter situated at a point more or less distant.

15 The general object of the invention is to increase the rapidity and certainty of operation of such an apparatus, and to provide improved means of maintaining the synchronism between the transmitting-cylinder at the sending-sta-
20 tion and the type-wheel at the receiving station or stations, by causing the same to be regulated or adjusted automatically once during each revolution, instead of at regular intervals and at the will of the transmitting-operator, as
25 in the apparatus heretofore in general use.

To this end my invention consists, first, in making use of an electro magnet or magnets for controlling the movement of the type-wheel, together with an independent electro-magnet
30 in the same circuit for controlling the impres-
sion device, in combination with a shunt or branch circuit around the impression-magnet only, which is momentarily closed at a given point once in each and every revolution of the
35 type-wheel by a device moving synchronously with the type-wheel, whereby the unison device may be operated by means of an increased current without affecting the printing mechanism; second, in the combination of a type-
40 wheel, a step-by-step escapement actuated by an electro magnet or magnets for controlling the same, and a unison-stop, which automatically locks the type-wheel at the zero-point and releases it by the action of the said electro-
45 magnet when traversed by a current of increased strength, whereby the said unison-stop may be operated from the type-wheel magnet; third, in the combination of an electro magnet or magnets for controlling the movements of
50 a type-wheel with a yielding stop, which limits the arc of vibration of the armature of said

electro-magnet so long as the said armature is under the influence of a normal current, and a unison-stop upon the type-wheel, which is controlled through the said yielding stop by increasing the normal strength of current traversing the type-wheel magnets; fourth, in the combination of an electro magnet or magnets for controlling the movements of a type-wheel, a yielding stop which limits the arc of vibration of the armature of said electro magnet or magnets when under the influence of a current of normal strength, with a unison detent or stop normally resting in the path of the type-wheel and adapted to arrest the same at the 65 zero-point, and a connection from said yielding stop to the unison-detent which withdraws the same and releases the type-wheel whenever the normal strength of current through the type-wheel magnet is increased; fifth, in 70 the combination of a rotating type-wheel, a unison-stop arranged to arrest the rotation of said type-wheel at the zero-point, and an electro-magnet which withdraws said stop and releases the type-wheel when the normal strength 75 of the current traversing its coils is increased, with a circuit-closer revolving synchronously with said type-wheel, and a unison-stop acting to momentarily increase the strength of current in said electro-magnets simultaneously with 80 the arrest of the type-wheel by the unison-stop, whereby the cutting out of the resistance of the printing-magnet assists in strengthening the current for operating the unison mechanism; sixth, in the combination of a type-wheel, an 85 electro magnet or magnets, an armature, a yielding stop for limiting the arc of vibration of said armature, and a rock-shaft upon which the said yielding shaft and unison-detent are mounted.

90 In the accompanying drawings, Figure 1 is a front elevation of a printing-telegraph instrument embodying my improvements. Fig. 2 is a vertical transverse section of the same. Fig. 3 is a detached view, in elevation, of a portion 95 of the mechanism. Fig. 4 is a skeleton view, illustrating the electrical connections of the apparatus; and Fig. 5 is a detached view, in perspective, of certain details of the mechanism.

100 The complete apparatus may be said to consist of three sets of mechanism, the first of

which produces and controls the intermittent rotation of the type-wheel, the second produces the impression of the proper letter upon the paper and moves the paper forward to the 5 type-wheel, as required, and the third controls the synchronism of the type-wheel with the transmitting apparatus at the distant station, and restores the same to its proper position or relation when it is thrown out of correspondence by accident or otherwise.

The first part of the apparatus consists of a type-wheel, A, having any required letters, figures, or other characters engraved upon its periphery. The type-wheel is mounted upon 15 an arbor, *a*, to which is also fixed a scape-wheel, B. The type-wheel and scape-wheel tend to rotate continuously in the direction of the arrow in Fig. 1, impelled by a train of wheel-work, C C, which receives its motion 20 from the barrel *c* and cord *c'*, to which a weight is attached, and which may be wound up as required by applying a key to the post *c''*. The type-wheel is held in check by an anchor-escapement, D, whose pallets engage alternately 25 with opposite teeth of the scape-wheel B. The escapement D is fixed to a rock-shaft, *d*, from which projects an arm, *e*, carrying an armature, E.

The hereinbefore-described mechanism is 30 old and well-known, and by itself forms no part of my invention; but I make use of a novel construction and arrangement of electro-magnets for producing the vibration of the armature E, by which the step-by-step advance of 35 the type-wheel A is produced through the agency of the escapement B.

Two electro-magnets, F and F', are arranged with their poles facing toward each other upon opposite sides of the armature E, as best seen 40 in Figs. 3 and 4. The yoke or back armature of each of these electro-magnets, instead of being made of soft iron in the usual manner, consists of a permanent steel magnet of horseshoe shape, into the opposite poles, *n* and *s*, of which 45 the respective cores of the electro-magnets are firmly screwed or otherwise secured. The permanent magnet induces corresponding polarity in the soft-iron cores attached to its poles, and thus they are rendered in effect permanently 50 magnetic, but of opposite polarity. I prefer to arrange the electro-magnets F and F' with their similar poles facing each other, the north pole of F facing the north pole of F', and the south poles in like manner, in which case the 55 armature E, being a neutral piece of soft iron, will be attracted indifferently by either pair of cores when no current is passing. The helices or coils are so arranged that the direction of the current through them in reference to the 60 normal magnetism of the cores will produce an opposite effect in the two electro-magnets. Thus, for example, a positive current will generate an electro-magnetism which will reinforce and strengthen the normal magnetism of 65 the electro-magnet F, and partially or wholly neutralize that of the electro-magnet F'. The

armature E will therefore be strongly attracted by F, and slightly or not at all by F'. A negative current, on the contrary, will strengthen the normal magnetism of F' and neutralize 70 that of F, causing the armature E to be attracted in the opposite direction. Thus, by transmitting alternate pulsations of positive and negative electricity through both electro-magnets (these being included in the same circuit) the armature E may be made to vibrate 75 to and fro with great rapidity.

An important advantage of the arrangement which I have described consists in the use of a non-polarized armature in lieu of the polarized armature heretofore used, whereby I am enabled to make this armature exceedingly 80 small and light. This could not well be done in the case of a polarized armature, in consequence of the danger of demagnetization when 85 the mass of metal is small, which, in practice, is found to be a very serious evil. This objection is entirely overcome by the arrangement which I have described.

The printing mechanism consists of a lever, 90 H, fixed upon an arbor or shaft, *h*, which carries a cylindrical pad or platen, I, and a paper-feeding mechanism, J, of the usual construction, by means of which a paper ribbon or tape, *j*, is drawn forward to receive the impression 95 of the successive characters as required.

K is an electro-magnet, which actuates the printing-lever by direct action upon its armature *k*, which is attached to the axis *h* of the printing-lever H by means of an adjustable 100 device, which is shown in dotted lines in Fig. 1, but will be best understood by reference to the detail perspective view, Fig. 5. The armature *k* is mounted upon an arm, *k'*. This arm is loose upon the shaft *h*, and has a downward 105 projection or arm, *k''*. Parallel to this latter is another arm, *h'*, which is rigidly attached to the axis *h*. The arms *h'* and *k''* may be adjusted toward or from each other by means of the screws *i* and *i'*. The screw *i* passes loosely 110 through the arm *k''*, and is tapped into the arm *h'*, while the screw *i'* is tapped through the arm *k''* and merely bears against the arm *h'*. By this means the force with which the platen I is pressed against the type-wheel A by the 115 action of the electro-magnet K upon its armature may be adjusted with great accuracy simply by loosening the screw *i* and tightening the screw *i'*, or vice versa, as required. The printing-magnet K is included in the same 120 circuit with the magnets F and F', which control the movement of the type-wheel, and is actuated when required simply by increasing the strength of the current, (irrespective of its 125 polarity,) by which the final movement of the type-wheel is effected in order to bring the proper character opposite the platen for printing, the ordinary pulsations, which are of sufficient strength to operate the type-wheel armature, being altogether insufficient to actuate 130 the printing devices.

The unison mechanism consists of a detent,

L, affixed to one end of a rock-shaft, l, and which, by means of an adjustable spring, L', is normally held in a position directly in the path of the pin or stop M, which is inserted in 5 the type-wheel A and revolves with it. When the pin M in its revolution comes in contact with the end of the detent L the type-wheel is arrested at the zero or starting point, and there held, notwithstanding the action of the escapement and wheel-work, until the detent is withdrawn. If the type-wheel is moving in unison with the transmitting-cylinder a pulsation of considerably more than the normal strength of current, which is sent through the line by 10 the transmitter at the moment of passing the zero-point, withdraws the detent or stop L, as hereinafter shown, and allows the pin M to pass by; consequently the progressive movement of the type-wheel is not arrested. But 15 in case the type-wheel is thrown out of correspondence with the transmitter by reason of any disarrangement of the conductors or the mechanism or other cause, so as to fall one or more steps behind the transmitter, the pin M 20 will not reach the stop in time to pass by it at the moment of its withdrawal, and the type-wheel will therefore be arrested and held by the detent L until the latter is withdrawn by the action of the transmitter in the next succeeding revolution, when the type-wheel will 25 necessarily start in unison with the transmitter. Thus the position of the type-wheel is automatically corrected, if found wrong, upon reaching the zero-point in each revolution.

30 The withdrawal of the detent L from the path of the pin M is effected by a device which will now be described.

The motion in each direction of the armature E, which carries with it the escapement, 35 is limited by the pendulum-arm N, (see Figs. 2, 3, and 4,) which is fixed upon the same axis d, and vibrates between two adjustable stops, O and P. The stop O is secured permanently to the frame of the instrument, but the stop 40 P is mounted upon a short arm, p, secured to the rock-shaft l, which carries the detent L. The tension of the spring L', Fig. 1, is sufficient to hold the stop P in the position shown in the drawings, except when a pulsation of increased strength is sent, when the tension of 45 the spring is overcome and the stop P yields slightly, falling back against the stationary block p', and at the same time withdrawing the detent L from the path of the pin M on the type-wheel.

50 As the printing mechanism, as well as the mechanism for correcting the type-wheel, are both set in action by a pulsation of increased strength, it is necessary to make provision for preventing the impression device from operating whenever a pulsation is sent for the purpose of withdrawing the unison-stop. This I effect by means of a rotating contact-point, r, upon the type-wheel, which touches an insulated spring, s, during each revolution at the 55 instant the pin M is passing the stop L. This

closes a shunt-circuit around the printing-magnet K and momentarily cuts it out of circuit while the unison device is being operated, and thus prevents the printing mechanism from 70 operating. Another important function of this circuit-closer and shunt is that it reduces the resistance of the main circuit by the amount of the resistance of the printing-magnet K, and to that extent increases the strength of the 75 current in the line at the moment the unison mechanism is to be operated. This in many cases is sufficient to effect the release of the unison-stop without the employment of additional cells of battery at the transmitting-sta- 80 tion for this purpose.

The general arrangement of circuits and mechanism, which has been hereinbefore described and explained, is clearly shown in Fig. 4, in which T and T' are the binding-screws 85 for the attachment of the line-wires. The normal circuit through the instrument is from T by wire 1 to electro-magnet F, thence by wire 2 to electro-magnet F', thence by wires 3 4 5 to printing-magnet K, thence by wire 6 to the 90 other binding-screw, T'. The shunt-circuit, which cuts out the printing-magnet K, starts from the point 4, between the type-wheel magnets F F' and the printing-magnet K, and goes through the frame of the instrument to the 95 hub of the type-wheel A, and thence through contact-point r, spring s, (when the latter is in contact,) and wire 8 to the binding-post T', where it rejoins the main wire. Thus it will be understood that the three principal working parts of the apparatus are operated by 100 three different strengths of current. The normal strength of current, which is also the weakest, is sufficient to actuate the escapement controlling the type-wheel by reversals of polarity, but not sufficient to effect the printing or to withdraw the unison-stop. A certain additional strength is sufficient to effect the printing also, but not to withdraw the unison-stop, which can only be done by the aid of a still 105 stronger current, and this last is prevented from operating the printing-magnet by the shunting device hereinbefore described. The action of the printing and unison devices is of course wholly independent of the polarity of 110 the current.

I am aware that printing-telegraphs have 115 been constructed in which a shunt passing round the printing-magnet has been closed at a determinate point in the revolution of the 120 type-wheel, provided that it has previously been completed at another point, but not otherwise, the last-named operation being under control of the transmitting-operator, and not automatic, and the shunt remaining continuously closed until broken by the act of the operator. My invention differs from this in that the shunt-circuit is momentarily and automatically closed at a determinate point once in each and every revolution of the type-wheel.

I am also aware that printing-telegraphs 130 have been constructed with automatically-lock-

ing unison-stops, which have been released either by the action of the printing-magnet or of an independent special magnet, and, in some cases, by the aid of a current of increased strength. In my invention the type-wheel is automatically locked at zero, and is released by the action of the type-wheel magnet when traversed by a current of increased strength.

I am furthermore aware that printing-telegraphs have been constructed having an automatic unison-stop and a type-wheel escapement provided with two pallets, one of which may be moved independently of the other, and with an independent electro-magnet for moving the last-named pallet and releasing the type-wheel at the zero-point.

I do not claim herein the combination of a non-polarized armature common to two electro-magnets, each of which has its cores polarized oppositely to each other by a permanent magnet, and both being arranged with poles respectively facing each other upon opposite sides of the armature, and with coils or helices united in the same circuit in such a manner that a positive current traversing them tends to neutralize the permanent magnetism of the electro-magnet on one side of the armature and to increase that of the electro-magnet on the opposite side thereof, while a negative current will tend to produce a converse of said action. Neither do I claim the hereinbefore-described method of operating a printing-telegraph instrument by currents of three different strengths, as these features of my invention will constitute a portion of the subject-matter of another application to be hereafter made by me.

I claim as my invention—

1. The combination, substantially as hereinbefore set forth, of an electro magnet or magnets for controlling the movements of a rotating type-wheel, an independent electro-magnet in the same circuit for controlling the printing mechanism, and a shunt or branch circuit around the printing-magnet only, which is momentarily closed at a determinate point once in each and every revolution of the type-wheel by a device moving synchronously with the type-wheel.
2. The combination, substantially as hereinbefore set forth, of a rotating type-wheel, a step-by-step escapement, an electro-magnet for actuating and controlling the same, a unison-stop which automatically locks the type-wheel at the zero-point against the action of the escapement and releases it by the action of the

said electro-magnet when the normal strength of current traversing the said magnet is augmented.

3. The combination, substantially as hereinbefore set forth, of an electro magnet or magnets for controlling the movements of a rotating type-wheel, a yielding stop which limits the arc of vibration of the armature of said electro-magnet while the latter is under the influence of a normal current, and a unison-stop upon the type-wheel which is controlled through the yielding stop by increasing the normal strength of magnetism in the type-wheel magnets.

4. The combination, substantially as hereinbefore set forth, of an electro magnet or magnets for controlling the movements of a rotating type-wheel, a yielding stop which limits the arc of vibration of the armature of said electro magnet or magnets when under the influence of a current of normal strength, a unison detent or stop normally resting in the path of the type-wheel and adapted to arrest the same at the zero-point in each revolution, and a connection from the said yielding stop to the unison-detent which withdraws the same and releases the type-wheel whenever the normal strength of current through the type-wheel magnet is increased.

5. The combination, substantially as hereinbefore set forth, of a rotating type-wheel, a unison detent or stop adapted to arrest the rotation of said type-wheel at the zero-point in each revolution, an electro-magnet which withdraws said stop and releases the type-wheel when the normal strength of the current traversing its coils is increased, and a circuit-closer revolving synchronously with said type-wheel and acting to momentarily increase the strength of current in said electro-magnet simultaneously with the arrest of the type-wheel by the unison-stop.

6. The combination, substantially as hereinbefore set forth, of a rotating type-wheel, an electro magnet or magnets, an armature, a yielding stop for limiting the arc of vibration of said armature, and a rock-shaft carrying the said yielding stop, and also a unison-detent, for locking the type-wheel.

In testimony whereof I have hereunto subscribed my name this 21st day of October, A. D. 1880.
